US00D516411S

(12) **United States Design Patent** (10) Patent No.: **US D516,411 S**
Millward et al. (45) Date of Patent: **** Mar. 7, 2006**

(54) **FACEPLATE**

(75) Inventors: **Devon Millward**, American Fork, UT (US); **Michelle Chatterton**, Lindon, UT (US); **Paul T. Clegg**, Lindon, UT (US); **Wallace E. Day**, Payson, UT (US)

(73) Assignee: **VIP Investments, Ltd.**, Orem, UT (US)

(**) Term: **14 Years**

(21) Appl. No.: **29/189,429**

(22) Filed: **Sep. 3, 2003**

(51) LOC (8) Cl. **11-05**

(52) U.S. Cl. **D8/353**

(58) Field of Classification Search D8/350-353, D8/14; D10/123, 108, 125; D13/171, 169, D13/156, 174, 158, 162; 174/66, 67; 200/304, 200/330; 40/732, 729

CLAIM

We claim the ornamental design for a faceplate, as shown and described.

DESCRIPTION

FIG. 1 is a front view thereof;

FIG. 2 is a side view thereof; and,

FIG. 3 is a top view thereof.

The broken line is for illustrative purposes only and forms no part of the claimed design.
